UNITED STATES PATENT OFFICE.

GEORGE F. HESS, OF PITTSBURG, KANSAS.

STEAM-PIPE FOR LOCOMOTIVE-ENGINES.

1,140,038.

Specification of Letters Patent. Patented May 18, 1915.

Application filed September 16, 1914. Serial No. 861,975.

To all whom it may concern:

Be it known that I, GEORGE F. HESS, of Pittsburg, in the county of Crawford and State of Kansas, have invented a certain new and useful Improvement in Steam-Pipes for Locomotive-Engines, of which improvement the following is a specification.

My invention relates to locomotive steam supply pipes, and more particularly to those 10 of the class termed "outside" steam pipes, and generally approved and applied in recent practice, in which the connection of the main steam supply pipe to the distribution valve chests is effected through pipes extending 15 through the shell of the smoke box, instead of, as in prior practice, through passages cored in the cylinder saddles. Outside steam pipes are of almost universal adoption in the latest designs of locomotives 20 of the various types now used, for the reason, particularly, that by their application, the lower portion of the smoke box is relieved from a substantial amount of steam pipe obstruction, with the result of improving 25 the draft and facilitating access to the interior of the smoke box, when required.

The object of my invention is to provide an outside steam pipe construction which shall be simple, inexpensive, and of ready 30 application in connection with valve chests which are either integral with the cylinders or detachable therefrom, and by the use of which, steam and air leaks into the smoke box, whether due to expansion and contraction 35 of pipes or to other causes, may be effectually prevented.

The improvement claimed is hereinafter fully set forth.

In the accompanying drawings: Figure 1. 40 is a side view, in elevation, of the right hand cylinder and valve chest, and the adjoining portion of the boiler, of a locomotive engine in which my invention is applied; Fig. 2, a central vertical transverse section through 45 the smoke box, the valve chest of the right hand cylinder being shown as integral therewith, and that of the left hand cylinder as detachable therefrom; and, Fig. 3, a partial longitudinal central section, on an enlarged 50 scale, through one of the steam pipes.

My invention is herein exemplified as applied in a locomotive engine the smoke box, 1, of the boiler, 2, of which, is, as in ordinary practice, supported on a pair of half saddles, 3, each of which is cast integral with a cylinder, 4, and which are secured

one to the other and to the side members, 5, of the locomotive frame. The supply and exhaust of steam, to and from the cylinders, are controlled, in the usual manner, by distribution valves of any suitable and preferred construction, which are fitted to be reciprocated, by proper valve actuating mechanisms, in valve chests, 6, 6^a, located above the cylinders. In the instance illustrated, the right hand valve chest, 6, is cast integral with the adjoining cylinder, and the left hand valve chest, 6^a, is a separate casting from the cylinder above which it is located, to which it is detachably connected 70 by bolts, 6^b.

The main steam pipe or dry pipe of the boiler, through which steam is supplied therefrom to the valve chests and cylinders, is, as usual, connected, at its forward end, 75 to a T head, 7^a, to each of the opposite ends of which there is connected a branch or side steam supply pipe, 8, which follows, as nearly as may be, the curvature of the smoke box, 2, and is located as close thereto as is 80 conveniently practicable. It will be obvious to those familiar with locomotive construction, that in cases where a superheater is applied, the side pipes will be connected to the superheated steam header thereof, in the ordinary manner. The side pipes, 8, extend outwardly through lateral openings, 2^a, in the smoke box, their outer ends projecting a short distance therefrom, and having circumferential flanges, 8^a, cast on them. The 85 lower ends of the side pipes are detachably connected to the distribution valve chests, through the intermediation of joint section pipes, 9, having circumferential flanges, 9^a and 9^b, on their upper and their lower ends, respectively, the upper flanges, 9^a, being secured to the lower flanges, 8^a, of the side pipes, by bolts, 10, and nuts, 10^a, and the lower flanges, 9^b, being similarly secured to flanges, 6^c, formed around steam admission 100 passages, 6^d, in the tops of the valve chests, 6, 6^a. Joint rings, 9^c, the faces of which are finished in the form of segments of spheres, are interposed between the adjoining flanges, and brought to a properly tight bearing 105 thereon by the connecting bolts and nuts, in order to insure steam tight joints.

It is, as is well recognized in the operation of locomotives, of material importance to prevent leakage of air into the smoke box, 110 and having this requirement in view, my invention is specially designed to enable air

5 tight joints between the side steam pipes, 8, and the smoke box, to be readily made and effectively maintained. To this end, a circumferential flange, 8^b, the outer face of which is curved to a radius of the inside of the smoke box, 2, or, correspondingly, of a reinforcing plate, 2^b, fitted therein, is formed on each of the side steam pipes, 8, said flanges fitting closely against the inside 10 of the smoke box or of the reinforcing plate, around the opening, 2^a, and being secured tightly to the smoke box by bolts, 8^c, and nuts, 8^d. Asbestos packing, 8^e, may, if desired, be fitted around the bolts, 8^c.

15 It will be seen that the construction above described presents the advantages, in addition to those of simplicity and inexpensiveness, of enabling a detachable valve chest to be readily removed and replaced whenever required, without breaking any joint between the adjoining steam pipe and the smoke box; of affording such flexibility in the connections between the T head and valve chests as facilitates accurate fitting 25 and allows for expansion and contraction under variations of temperature; of eliminating steam joints between the lower ends of the side steam pipes and their connections, inside of the smoke box; and of so making and locating the air joints between the pipes and smoke box that they are accessible from the outside of the smoke box and may be tightened by an ordinary calking tool whenever required.

30 35 While my invention is herein exemplified as applied with the form of smoke box which is most generally in use, that is to say, one which is directly interposed between the discharge ends of the tubes and the stack, it will be obvious that it is equally applicable in effecting the connection of a steam supply pipe to other portions of a boiler shell, as, for example, to the intermediate smoke boxes or combustion chambers of the large boilers of Mallet articulated locomotives. I do not, therefore, limit my invention to the specific location at

which the steam supply pipe is connected to the boiler shell, and in using the term "smoke box," intend it to apply to any 50 chamber or receptacle of a boiler through which products of combustion traverse in their passage from the tubes to the stack.

I claim as my invention and desire to secure by Letters Patent:

55 1. The combination, with a boiler having an opening in its shell, of a steam supply pipe which projects outwardly through said opening and is provided with a circumferential flange secured directly to the shell 60 around said opening, and a distribution valve chest connected to said pipe exteriorly to said opening.

2. The combination, with a boiler smoke box having an opening in its shell, of a 65 steam supply pipe which projects outwardly through said opening and is provided with a circumferential flange secured directly to the smoke box around said opening, and a distribution valve chest connected to said pipe exteriorly to said opening.

3. The combination of a boiler smoke box, a distribution valve chest, a steam supply pipe, and means for forming an air joint directly between said pipe and the smoke 75 box, and connecting said pipe and the valve chest through a steam joint wholly exterior to the smoke box.

4. The combination, with a boiler smoke box having an opening in its shell, of a 80 steam supply pipe which projects outwardly through said opening and is provided with a circumferential flange secured directly to the smoke box around said opening and a circumferential flange on its end exterior 85 thereto, a distribution valve chest, and a joint section interposed between, and connected at its opposite ends to, the outer end flange of the steam pipe and the valve chest.

GEORGE F. HESS.
